UNITED STATES PATENT OFFICE.

EBEN E. FULLER, OF LITTLEFALLS, MINNESOTA.

ROTARY ENGINE.

SPECIFICATION forming part of Letters Patent No. 727,122, dated May 5, 1903.

Application filed November 22, 1902. Serial No. 132,466. (No model.)

To all whom it may concern:

Be it known that I, EBEN E. FULLER, a citizen of the United States, residing at Littlefalls, in the county of Morrison and State of Minnesota, have invented certain new and useful Improvements in Rotary Engines; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in steam-engines, and especially in the provision in a rotary engine of a cylinder having a plurality of compartments and a shaft mounted eccentrically in the ends of the cylinder and compartment-wall and a piston positioned in each compartment and keyed to the shaft, with concentrically-rotating disks which are secured to a block carried by the pistons and in the partition, of wings one mounted in each compartment and fastened to disks which wipe against the inner circumference of the cylinder.

My invention relates, further, to various details of construction and combination of parts, which will be hereinafter more fully described and then specifically defined in the appended claims.

My invention is clearly illustrated in the accompanying drawings, which, with the letters of reference marked thereon, form a part of this application, and in which drawings similar letters of reference indicate like parts in the several views, in which—

Figure 1 is a vertical sectional view through one of the compartments of my improved rotary engine through a piston and shaft carrying the same. Fig. 2 is a longitudinal vertical section through the engine. Fig. 3 is a similar view showing a slight modification of the details. Fig. 4 is a side elevation of the disk, which has secured thereto a wing mounted in the piston. Fig. 5 is a detailed view of the disk with an eccentric aperture therein for the reception of the shaft of the engine. Fig. 6 is a sectional view of a wing and portions of disks to which it is secured.

Reference now being had to the details of

the drawings by letter, A designates the cylinder of the engine, which is cored out or recessed at A' to receive the abutments a a. 55

B represents solid pistons, which are keyed to the shaft B'.

In the drawings I have shown the cylinder divided into two compartments, and in each compartment is a similarly-mounted piston 60 B, and said shaft is mounted to have bearings in the eccentrically-formed apertures F in the disks F, there being preferably one of said disks F intermediate the two compartments, forming a wall between the two 65 chambers, and also at the outer ends of the cylinder. These disks F are held in place, preferably, by means of bolts passing through the shell of the cylinder and into the periphery of the disks, those at the ends of the cylinder being controlled by compensating or temper screws f. Each piston has mounted in a recess in its circumference a cylindrical block B², which block is transversely slotted to receive a wing C, and the ends of each 75 wing C are fastened, by means of lag-screws C', in radial grooves in the circular disks E, which have concentric apertures therein, which apertures are of considerably larger diameter than the diameter of the shaft for 80 a purpose which will hereinafter appear.

The circumferences of the disks E fit the inner circumference of the compartments of the cylinder as snugly as consistent with their rotating within the cylinders without undue 85 friction, and the wings C are positioned in the respective pistons in positions diametrically opposite for the purpose of allowing steam to enter one compartment of the cylinder simultaneously with the expanding of 90 the steam in the second compartment of the cylinder, thereby causing the force of the steam to bear continuously upon the rotating shaft.

As the disks E are circular and conform to 95 the shape of the inner circumference of the cylinder and as the pistons are mounted eccentrically within the cylinder, it will be observed that as the steam comes in contact with the wing C the piston will be rotated 100 with the wing, and by reason of the wings being fastened to the disks E the latter will rotate in stationary positions, which will cause the wings to have a reciprocating

movement, so that the outer edges thereof will wipe against the inner circumferences of the cylinder-chambers.

In Fig. 3 I have shown a slight modification, 5 in which the disks F are provided with bosses F², the purpose of which is to carry the washers E and find thereon their bearings instead of on their peripheries, as would be the case in the construction illustrated in Fig. 2 of the 10 drawings.

The inlet-port for the steam when driving the piston in one direction is illustrated in Fig. 1 by letter K and the exhaust by letter K', and when the engine is driven in the reverse direction the steam will enter the port 15 K' and exhaust through the port K.

The operation of my invention is as follows: In running the engine to the right, as indicated by an arrow in Fig. 1 of the drawings, steam is admitted through the port K, and as it enters it comes in contact with the abutment a and being deflected thereby comes in contact with the wing C, forcing it around to the right, and as said wing is confined in the block which is carried by the piston B and as said piston is keyed to the operating-shaft B' the latter will be rotated. Steam is admitted to the cylinder and acts upon the wing C during a one-half rotation of the piston, or until 25 said wing reaches the position indicated by dotted lines at C², and when the wing reaches said position the cut off takes place and the expansion of the steam within the chamber begins. It will be observed that while the 30 wing C in one compartment of the cylinder is turned to occupy the position designated by C² the corresponding wing in the second compartment will have passed from the position shown by dotted lines in Fig. 2 to a 35 position corresponding to the position shown by the wing C in Fig. 1 and steam will be admitted to the second compartment of the cylinder, and it will be observed that when cut off takes place in one section of the cylinder steam is admitted to the other, so that 40 at every point of revolution steam is entering one section and expansion is going on in the other alternately. To reverse the engine, steam is admitted at port K' and exhaust is 45 made at port K and the operation is the same. 50

From the foregoing it will be observed that many advantages may be obtained from a multisection cylinder over the common types of rotary engines in which a plurality of the 55 wings are employed and in which the expansive force of the steam is not utilized, as by the provision of the two compartments of the cylinder each having a piston with single wings alternately arranged power is applied 60 to the shaft during its complete revolution, thus overcoming the troublesome feature known as "dead-point."

Some of the advantages secured by an invention made in accordance with my invention 65 whereby the expansive force of the steam is utilized will be noted in the crescent-shaped space between the shell and the piston and

which is occupied by steam when in operation.

Referring to Fig. 1, it will be noted that 70 steam is turned on through the port K until the wing C reaches the position C², which amounts to a one-half revolution, after which the port K is closed and no more steam is admitted to that section until the revolution is 75 completed.

It will be noted that the shape of the space in the cylinder between C² and the exit-port K' is crescent-shaped and adapted to be filled by the expanding steam as the wing advances 80 in its travel, said space being crescent-shaped with its point away from the advancing wing, and consequently the tax upon the expanding volume is greatly lessened as the point of exit is approached. It is apparent, then, that 85 the expanding steam parts with its elasticity at a slower rate and that a higher rate of efficiency is maintained than would be the case if the space were of a different shape.

By the provision of an invention made in 90 accordance with my invention no uncertain features, as springs, weights, &c., are employed. Each movement has positive rotating parts, which are well-balanced, and hence a high rate of speed may be safely maintained, 95 and the parts which are most subject to wear and leakage are made adjustable, and an effective means is provided to accomplish the results sought for.

Having thus described my invention, what 100 I claim as new, and desire to secure by Letters Patent, is—

1. A rotary steam-engine, comprising a cylinder, a plurality of compartments therein, with steam inlet and exit ports, a shaft 105 mounted eccentrically in the ends of said cylinder and the compartment-wall, a piston positioned in each compartment and keyed to said shaft, concentrically - rotating disks mounted within each compartment, a block 110 mounted in a recess in each piston, and a wing movably held by said block and fastened at its ends to said disks and adapted to wipe against the inner circumference of the cylinder as the wing is driven forward by 115 steam coming in contact therewith, as set forth.

2. A rotary engine, comprising a cylinder having a plurality of compartments therein, with steam inlet and exit ports, shaft-supporting disks mounted in the outer ends of the cylinder, compensating screws bearing against said disks, a similar disk forming a partition-wall between said compartments, a piston positioned in each compartment, a 125 shaft eccentrically mounted in said disks to which the pistons are keyed, a movable wing mounted in a recess in each piston, circular disks, with central apertures, mounted within each compartment and secured to said 130 wing, the latter adapted as the piston rotates to wipe against the inner circumference of the cylinder, as set forth.

3. A rotary engine, comprising a cylinder

with a plurality of compartments therein, steam inlet and exit ports, a shaft mounted eccentrically within said cylinder, a piston positioned in each compartment and keyed to said shaft, a wing having a reciprocating movement in the recess in each piston, circular disks with central apertures mounted within each compartment and having radial grooves in which the opposite ends of said wing are seated and fastened, the outer edges of each wing adapted to wipe against the in-

ner circumference of the cylinder, the two wings arranged in diametrically opposite relation, whereby the force of the steam may continuously bear against the rotating shaft, 15 as set forth.

In testimony whereof I hereunto affix my signature in presence of two witnesses.

EBEN E. FULLER.
